UNITED STATES PATENT OFFICE.

ARTHUR R. KRAUSE, OF WOODHAVEN, NEW YORK, ASSIGNOR TO LION ELECTRIC MANUFACTURING CO. INC., A CORPORATION OF NEW YORK.

DESIGN FOR A BACKPLATE FOR LIGHTING FIXTURES OR SIMILAR ARTICLES.

Application filed November 22, 1924. Serial No. 11,450. Term of patent $3\frac{1}{2}$ years.

To all whom it may concern:

Be it known that I, ARTHUR R. KRAUSE, a citizen of the United States, and a resident of Woodhaven, county of Queens, and State of New York, have invented a new, original, and ornamental Design for Back-plates for Lighting Fixtures or Similar Articles, of which the following is a specification, reference being had to the accompanying drawing, forming a part hereof.

In these drawings:

Fig. 1 is a front elevation of the back plate for lighting fixtures or similar arti-

cles, the part shown in full line outline in the drawing being ornamented in the same manner as the portion more fully illustrated; and

Fig. 2 is a side elevation, in diagrammatic outline, of the back plate for lighting fixtures or similar articles.

I claim:

The ornamental design for a backplate for lighting fixtures or similar articles substantially as shown and described.

ARTHUR R. KRAUSE.
